UNITED STATES PATENT OFFICE.

MARSHALL H. FARNSWORTH, OF BROOKLYN VILLAGE, ASSIGNOR TO THE OHIO WOODEN WARE MANUFACTURING COMPANY, OF CLEVELAND, OHIO.

WASH-BOARD PROTECTOR.

SPECIFICATION forming part of Letters Patent No. 258,904, dated June 6, 1882.

Application filed October 19, 1881. (No model.)

To all whom it may concern:

Be it known that I, MARSHALL H. FARNSWORTH, of Brooklyn Village, in the county of Cuyahoga and State of Ohio, have invented a 5 certain new and Improved Wash-Board Protector; and I do hereby declare that the following is a full, clear, and complete description thereof.

The nature of this invention relates to wash- 10 board protectors; and it consists in connecting with an ordinary wash-board a semi-cylindrical or curved protector, provided with metallic or wood ends, in which is a curved slot, through which passes into the sides a pin or 15 stud. The protector rolls or slides upon this stud, and is retained in place thereby when either rolled out for use or turned back into the wash-board.

This improvement is susceptible of various 20 modifications without departing from the nature of the invention.

That others may more fully understand the construction and operation of the said invention, reference will be had to the following 25 specification, and to the annexed drawings, making part of the same.

Figure 1 is a plan view, showing the protector in place in a wash-board. Fig. 2 is a longitudinal section in the direction of the line 30 $x x$, Fig. 1. - Fig. 3 is a view of the protector detached from the wash-board.

Like letters of reference refer to like parts in the several views.

A is a wash-board, which may be constructed 35 in the ordinary manner, and to which is connected the improved adjustable protector B. This protector may be of wood or sheet metal, zinc being the preferred metal. The ends of the protector may be of metal, and nailed or 40 otherwise secured to the wooden curved part thereof, and the metal ends may be formed with a flange to lap over the outside of the protector. In the end pieces, C C, are curved slots a , Figs. 2, 3, through which pass pins D 45 into the sides E E of the wash-board, as seen in Fig. 1. These pins hold the protector in position either for use or packing up for transportation.

The protector, by means of the curved slots a and the pins D D, may be made to slide 50 or be rolled out from the position indicated at $c c$ to that of c' , Fig. 2. When it is extended it is ready for use, and when rolled or turned back to $c c$ it is ready for packing, one wash-board upon another, so as to take up but little 55 room, for transportation.

Instead of the slots a being in the end piece, they may be in the sides of the frame, the studs D D extending from the ends of the protector into the said slots, which would be essentially the same as the arrangement herein shown, and preferred for the purpose designed.

The semi-cylindrical shape of the protector permits of its being easily attached to the wash-board and to slide between the side pieces 65 thereof, to adjust it to protect the person using the board, and for sliding it down between the sides for the convenience of packing the wash-boards for transportation. The protector, when drawn out for practical use, presents an exterior curved surface to the person using the board to lean upon, while the inner surface deflects and throws back the splashing water 70 into the tub.

To retain the protector in the position indicated at c' for use, the edge d is caused to drop or is forced into the groove e , Fig. 2, which extends across the back piece, F, and on raising the protector it is readily moved out of the groove, that it may be rolled back to within 80 the frame of the wash-board, as indicated at $c c$, so that it is below or flush with it.

The rubbing-surface G of the board is or may be the same as in common use, and connected with the frame in the usual way.

What I claim as my invention, and desire to secure by Letters Patent, is—

1. A protector in combination with the upper part of a wash-board, and connecting devices between the side pieces thereof, arranged 90 substantially as described, whereby the protector may slide between said sides, as and for the purposes set forth.

2. A wash-board provided with a groove or notch, e , the connecting devices, consisting of 95 a slot and tenon, and the protector, all in com-

bination, and arranged to operate in the manner substantially as described, and for the purpose set forth.

3. In a wash-board, a semi-cylindrical protector adapted to roll or slide within the sides thereof and provided with ends having curved slots therein and pins extending from the said sides into the slots, respectively, whereby the protector is retained in position for use or for be-

ing packed for transportation, substantially as set forth.

In testimony whereof I affix my signature in presence of two witnesses.

MARSHALL H. FARNSWORTH:
